US00D929412S

(12) **United States Design Patent** (10) Patent No.: **US D929,412 S**
 McDonald et al. (45) Date of Patent: **** Aug. 31, 2021**

(54) **DISPLAY SCREEN OR PORTION THEREOF WITH GRAPHICAL USER INTERFACE**

(71) Applicant: **Carrier Corporation**, Palm Beach Gardens, FL (US)

(72) Inventors: **Patrick McDonald**, Athens, GA (US); **John F. Hannon**, Pennellville, NY (US); **Mark Fragnito**, Watkinsville, GA (US); **Deborah A. Champagne**, Syracuse, NY (US); **Thaison Phan**, Syracuse, NY (US); **Ken Shuart**, Danielsville, GA (US); **Vohn McLeish**, Athens, GA (US)

(73) Assignee: **CARRIER CORPORATION**, Palm Beach Gardens, FL (US)

(**) Term: **15 Years**

(21) Appl. No.: **29/701,185**

(22) Filed: **Aug. 8, 2019**

(51) LOC (13) Cl. **14-04**

(52) U.S. Cl.

USPC **D14/485**

CLAIM

We claim, the ornamental design for a display screen or portion thereof with graphical user interface, as shown and described.

DESCRIPTION

The FIGURE is a front view of a display screen or portion thereof with graphical user interface, showing our new design.

The broken lines in the FIGURE represent no part of the claimed design.
